(57) **CLAIM**

The ornamental design for an electrical connector, as shown and described.

DESCRIPTION

Cross reference is made to U.S. design patent application Ser. No. 29/864,718 entitled "Electrical Connection System" by Georg Wallensteiner, which was filed on even date herewith; and U.S. design patent application Ser. No. 29/864,720 entitled "Electrical Connector" by Georg Wallensteiner, which was filed on even date herewith.

FIG. 1 is a perspective view of an electrical connector showing my new design;

FIG. 2 is a left side elevational view of the electrical connector of FIG. 1;

FIG. 3 is a right side elevational view of the electrical connector of FIG. 1;

FIG. 4 is a front side elevational view of the electrical connector of FIG. 1;

FIG. 5 is a rear side elevational view of the electrical connector of FIG. 1;

FIG. 6 is a top side plan view of the electrical connector of FIG. 1; and,

FIG. 7 is a bottom side plan view of the electrical connector of FIG. 1.

The evenly dashed broken lines shown in the drawings illustrate portions of the electrical connection device that form no part of the claimed design. The electrical connection device is shown with a dash-dot-dash symbolic break in its length. The appearance of any portion of article beyond the break lines forms no part of the claimed design.

1 Claim, 7 Drawing Sheets
